UNITED STATES PATENT OFFICE.

SETH HOOTMAN, OF KINGSTON, MISSOURI.

BUGGY-WHIP.

1,161,129.

Specification of Letters Patent. Patented Nov. 23, 1915.

Application filed December 7, 1912. Serial No. 735,435.

To all whom it may concern:

Be it known that I, SETH HOOTMAN, a citizen of the United States, and a resident of Kingston, in the county of Caldwell and State of Missouri, have invented certain new and useful Improvements in Buggy-Whips, of which the following is a specification, reference being had to the accompanying drawings.

10 This invention relates to certain new and useful improvements in buggy whips.

The primary object of my invention is to provide a buggy whip which will keep its form, and will not break or bend over at the tip.

Another object is to provide a buggy whip with a spring steel filler, the surface of which is traversed by a spirally running groove within which the cover is firmly held 20 to hold the same against casual displacement.

A further object is to provide a buggy whip of a simple and comparatively inexpensive nature and of a lasting and durable 25 construction which will be pliable and include a grooved metal filler ending at the tip end in an eye and at the butt end in an outstanding flange.

With these and other objects in view, the 30 present invention consists in the combination and arrangement of parts as will be herein-after more fully described and finally pointed out in the appended claim, it being further understood that changes in the specific 35 structure shown and described may be made within the scope of the claim, without departing from the spirit of the invention.

In the accompanying drawings forming a part of this specification, and in which like 40 numerals of reference indicate similar parts in the several views: Figure 1, shows a view with parts broken away of a whip embodying my invention. Fig. 2, is a sectional view of Fig. 1. Fig. 3, shows a sectional view 45 of a portion of the whip.

A buggy whip unless some special provision is made to hold the same in shape will bend over at the tip owing to the effect of the weather and use. In my present invention I provide a whip which will be pliable 50 while at the same time retaining at all times

its shape in that I provide the same with a spring steel filler.

In the drawings the numeral 1, indicates a tapering spring steel member which at the 55 butt end has the outstanding flange 2 and at the tapering end, ends in the eye 3. This member which has a smooth and polished surface when finished is traversed by a spirally running groove α . This groove not only 60 makes the metal member light but provides a depression within which the whip covering 4 is held, thus preventing the cover slipping or becoming casually displaced upon the member as might be the result if no corrugation were provided. At its lower end the 65 flange 2 protects the lower end of the covering while at the upper end, the covering ends adjacent to the eye 3, to which is secured a lash 5. Such a whip will absolutely 70 keep its shape and owing to the fact that the member is made of spring steel, it will be sufficiently pliable so that the whip can be conveniently wielded without danger of breaking the same. The spiral groove α 75 is of such a width that the weight of the stock can be nicely regulated in that the unnecessary metal is removed through the intermedium of the groove which can be wide and shallow or narrow and deep. 80

A whip constructed according to my invention is simple and both durable and efficient in operation.

Having thus described my said invention, what I claim as new and desire to secure by 85 United States Letters Patent is:

A whip comprising a tapering member made of a single length of spring steel having an integral outstanding flange at the butt end and an eye at the other end, said 90 member being traversed from end to end by a spiral groove, in combination with a cover woven over said member and pressed into said spiral groove and secured therein and stopped against said flange and eye at its 95 ends.

In testimony whereof I affix my signature, in presence of two witnesses.

SETH HOOTMAN.

Witnesses:

D. O. LOVE,
H. C. SHIVELY.
